UNITED STATES PATENT OFFICE.

BENJAMIN T. HOLMAN, OF SEWICKLEY TOWNSHIP, ALLEGHENY COUNTY, PENNSYLVANIA, ASSIGNOR OF ONE-HALF TO KARL J. ECKERT, OF ECONOMY TOWNSHIP, PENNSYLVANIA.

SPUDDING SHOE.

1,409,177.

Specification of Letters Patent. Patented Mar. 14, 1922.

Application filed February 12, 1921. Serial No. 444,556.

To all whom it may concern:

Be it known that I, BENJAMIN T. HOLMAN, a citizen of the United States, and residing in the township of Sewickley in the county of Allegheny and State of Pennsylvania, have invented or discovered the new, useful, and Improved Spudding Shoes, of which the following is a specification.

My invention consists in a new and improved spudding shoe.

In well drilling, until the well is deep enough to permit the use of the walking beam, the operation of the drilling tool is accomplished by means of a spudding shoe 15 engaging the cable between the bull wheel and the crown pulley, and connected to a jerk rope attached to the crank of the band wheel.

The object which I have in view is the provision of a spudding shoe which may be installed on the cable and attached to the jerk rope by one person, which will be efficient in operation, which one person may dismount and disconnect, and which in case 25 the jerk rope breaks or loosens from the spudding shoe, will not fly off the cable to the damage of property and lives.

Generally speaking my improved shoe comprises a head provided with an arcuate 30 grooved bearing adapted to be engaged by the cable, a shank pierced or otherwise provided with means for attaching the jerk rope, a fixed cheek on one side, connecting the head and shank, and an opposed cheek 35 pivotally mounted on the head and adapted to be swung into engagement with and be detachably connected to the shank, the cable being included between the two cheeks when the shoe is in use.

40 Other novel features of construction and arrangement of parts will appear from the following description.

In the accompanying drawings, Fig. 1 is a perspective of an improved spudding shoe 45 embodying the principles of my invention, the pivoted cheek being shown closed; Fig. 2 is a side elevation of the same, and Fig. 3 is a section taken along the line III—III in Fig. 2.

50 The following is a detailed description of the drawings.

A represents the head of the shoe provided with an arcuate grooved bearing or shoe-portion 1 to receive the drilling cable.

B is the fixed cheek portion rigidly connecting the head A with the shank C which is provided with an eye or hole 2 for the attachment of the jerk rope. The head, fixed cheek and shank may be formed of an integral casting.

D is the other cheek consisting of a plate which is pivotally connected to the head A as by the bolt 3. The rear edge of the cheek D is provided with an inturned L shaped flange 4 which, when the cheek D is turned 65 into its closed position, as shown in the drawings, engages and interlocks with a complementarily formed rib 5 on the face of shank C, said flange and rib being arcuate and concentric with the bolt 3 so that when 70 the cheek is swung out, the flange 4 slides into engagement with the rib 5, thereby preventing the cheek D from being forced or spread away from the shank, or in other words moved out of parallelism with the 75 fixed cheek B.

When opened, the cheek D swings in the direction indicated by the arrow in Figs. 1 and 2.

E is a locking latch having a reduced shank 80 bolted in a cut away portion 6 on the face of the shank C and having its enlarged head extending over the recess 7 in the face of said shank. The free end of said latch extends in the direction of the closing movement of the cheek D.

The head of said latch is enlarged, as at 8 to form a stop against which the recessed corner of the cheek D strikes, thus limiting the closing movement of said cheek. 90 The under side of the front portion of said cheek is undercut as at 9 to form at the edge of the cheek a tooth 10 which rides over a shoulder 11 on the latch and seats in the angular recess 12 between the shoulder 11 95 and the stop 8, the forward side of the shoulder being bevelled, as 13 to enable the tooth 10 to depress the latch sufficiently to engage the tooth 10 with the recess 12.

In practice, the cheek D is swung open and 100 the shoe placed on the cable. The cheek D is then swung closed, and as it closes, is automatically locked shut against accidental loosening. The jerk rope is then attached to the shank, and the band wheel started. 105 When it is desired to remove the spudding shoe from the cable, the workman pushes in the stop 8 until the shoulder 11 is forced in-

wardly out of engagement with the tooth 10, whereupon the cheek D may be swung open and the shoe lifted off the cable.

It is evident that the spudding shoe may 5 be readily installed and removed by one person. It is also evident that in case the jerk rope breaks or becomes accidentally detached from the spudding shoe, the latter will not fly off the cable, a source of frequent accident 10 in oil and gas well drilling, but will remain on cable, and no injuries result.

The recessing of the corner of the cheek plate and the fact that the end of the stop 8 is short of the outer face of the cheek D 15 prevents the stop 8 from being accidentally depressed to release or unlock the pivoted cheek.

What I desire to claim is:—

1. In a spudding shoe, the combination of 20 a head, an arcuate cable bearing fixedly carried by said head, a cheek and a shank in rigid relationship, a second cheek pivotally attached to said head and adapted to swing into and out of engagement with the shank, 25 and means for locking said second named cheek in engagement with said shank.

2. In a spudding shoe, the combination of 30 a head, an arcuate cable bearing fixedly mounted on said head, a cheek and a shank in rigid relationship, a second cheek pivotally attached to said head and adapted to swing into and out of engagement with the shank, and means whereby said pivoted cheek is automatically locked to said shank.

35 3. In a spudding shoe, the combination of a head, an arcuate cable bearing fixedly mounted on said head, a cheek and a shank

in rigid relationship, a second cheek pivotally attached to the head and adapted to swing, in parallelism with said first named 40 cheek, into and out of engagement with the shank, and means for locking said second cheek to said shank.

4. In a spudding shoe, the combination of 45 a head, an arcuate cable bearing fixedly mounted on said head, a cheek and a shank in rigid relationship, a second cheek pivotally attached to the head and adapted to swing, in parallelism with said first named 50 cheek, into and out of engagement with the shank, and automatic means for locking said second cheek to said shank.

5. In a spudding shoe, the combination of 55 a head, an arcuate cable bearing fixedly mounted on said head, a cheek and a shank in rigid relationship, a second cheek pivotally attached to the head and adapted to swing into and out of engagement with the shank, and means whereby said second cheek is prevented from spreading relative to said 60 first cheek when said second cheek is in engagement with said shank.

6. In a spudding shoe, the combination of 65 a head, an arcuate cable bearing fixedly mounted on said head, a cheek and a shank in rigid relationship, and a second cheek adapted to swing into and out of engagement with said shank, said second cheek and shank being provided with interengaging portions to prevent said second cheek from 70 spreading away from said first cheek.

Signed at Pittsburgh, Pa., this 10th day of Feby., 1921.

BENJAMIN T. HOLMAN.
